CLAIM

The ornamental design for an appliance control panel and screen, as shown and described.

DESCRIPTION

FIG. 1 is a front elevational view of an appliance control panel and screen showing my new design; and,

FIG. 2 is a perspective view of the appliance control panel and screen of FIG. 1.

The broken lines showing environment form no part of the claimed design.

1 Claim, 2 Drawing Sheets

FIG. 1

FIG. 2
